SPRAY DEVICE

Clara E. McNutt, Toledo, Ohio

Application September 11, 1946, Serial No. 696,083

2 Claims. (Cl. 299—88.5)

1

This invention relates to the conversion of a more or less viscous liquid into a spray, especially in the delivery thereof uniformly as a fog over an area or into a region say of loose hair on the head of an individual.

This invention has utility when incorporated in a jetting nozzle unit, particularly as an aspirator of such symmetrical liquid withdrawal rate as to thoroughly nebulize the projected volume symmetrically thruout the region of spread. The unit automatically retains these delivery characteristics, even for extended periods of discontinuous use, for the impinging fluid supply cut-off lacks liquid suction capacity for any entrance whatever into the pressure fluid discharge port. Furthermore, the absence of the lift action of the draft across the port bringing the liquid thereto for atomization, has riser duct proportion thereto provide such downflow volume at release that a meniscus is not developed across the fluid delivery port.

Referring to the drawings:

Fig. 1 is a side elevation, with major portions broken away, of an embodiment of the invention in a lacquer handling unit which may have special adaptation as an item of hair dressing equipment;

Fig. 2 is an enlarged vertical section thru the jet and nozzle assembly for the nebulizer feature of the disclosure in Fig. 1; and

Fig. 3 is a section on the line III—III, Fig. 2, before the liquid delivery nozzle is assembled with the jet fluid supply.

From a cylindrical base portion 1 a pressure air supply duct rises thru a flange collar 2 to an upwardly extending narrowing cross-section portion 3. At its upper end 4, the tapering section 3, has a radial or horizontally extending port or jet opening 5. In order better to centralize the spray means in a cup or flare chamber wall 6 having a bottom 7, which may be adherently assembled with the flange 2, the taper tubular portion 3 has an offset or major slant side 8 with a seat 9 having a bottom key 10. An aspirator tube or passage section 11 uniformly tapering thruout its extent upward to a top nozzle or port 12, has a centering notch 13 at its lower end 14 to register with the key 10. Plastic weld or adhesive assembly is accordingly effective in predetermining definitely that tip 12 has a specific spacing from and is but slightly above the lower side line and thereby approaching pressure flow impingement direction from the jet opening 5.

An endless seat 15 provides top bounds for the wall 6 in which is snugly fitted a base of a dome

16 having a window opening 17, which, at non-use intervals, may be closed by a cork or stopper 18.

An air pump or compressible downwardly flaring bulb 19 has friction fitting portion 20 to engage the tubular base 1. Remote from the portion 20, the bulb 19 has assembled therewith a sleeve or tube 21 having telescopic connection with the base 1 inward from and concentric with the portion 20. A fitting 22 for the tube 21 with the re-entrant central or axial region of the direct support or base portion of the bulb 19 is at an intake check valve 23, upwardly from which may be deposited a cartridge or lozenge 24 of volatilizable matter, such as perfume, in the event of tonsorial usage. Furthermore, it may carry at the cartridge a readily responsive air impregnating medium of treatment promotion properties, as of disinfectant or antiseptic values. With the bulb 19 firmly grasped and squeezed, the port entrance or check valve 23 is closed, and the reduced air volume for the bulb 19 has such air pass therefrom thru ports 25 upward to be forcibly ejected at the opening 5 at a velocity of such suction-effecting force across the top of the nozzle 12, that hair treating lacquer 26 rises in the upwardly tapering liquid supply tube 11 for dispersion into a spray or fog 27 in delivery outward thru the open window 17.

With a bulb 19 in the range of 3" diameter and 5" tall, the duct 1 running about $\frac{3}{8}$ " internal diameter, the jet opening 5 of around .076" diameter from a cross section region of the duct 3 of say .125" and the downward flare in the first inch of up to .187" diameter, there has been associated an aspirator. The nozzle of .058" diameter from a base inlet of .156" diameter had approximately $\frac{1}{4}$ " clearance from the bottom 7 of the vessel 6, 1. Spaced 6" from a vertical flat area, each compression of the bulb 19 will uniformly develop a mist or fog to define a pattern of oval shape $2\frac{1}{2}$ " high by 3" wide. Hair lacquer of an initial viscosity of $9\frac{1}{3}$ centipoise has such increased materially from the current use, due to volatilization therefrom. The vapor dispersion under the embodiment of the invention above specifically set forth is in the range of one tenth of a cubic centimeter for each pattern single bulb discharge. The spread is of extreme fineness for approximately doubling the field of effective spray use over current available acceptable market devices.

There is marked advantage in handling. The precise placement of the jet 5 as to the nozzle 12, is a factor in maintaining a good spread regular

oval pattern. The air projection volume and velocity as to the restriction of the aspirator cooperate in the elimination of even droplets and insuring nebulizing to great degree of fineness for the entire projected substance. The enlargements directly downward from the discharge regions, individually and jointly contribute materially to non-clog performance. The enlargement downward from the jet opening 5 is of such volume increase that the minor volume region of the discharge develops into a negligible factor. Practically this means that at the intermission of blowings from the jet 5, there is not suction sufficient to draw liquid thereinto from the nozzle 12. Furthermore, the tube 11 cross section increase away from the opening 12 has the downpull liquid volume therein effective against any surface tension or film meniscus bridging.

From the foregoing, it is apparent that for normal operation, the unit herein disclosed is self-cleaning, at least to a normally functioning or operative extent. However, in practice, there may be occasion, as for changing the liquid or solution being handled. The ready removal of the dome 16 exposes the vessel 6, 7, and the tube, from the nozzle 12 for swabbing and rinsing. Disconnection of the unit (Fig. 2), which may be of plastic, from the bulb and sleeve or stem 21, opens the taper portion 3 for thoro cleaning service.

For beauty parlor work, the device is a complete one-hand operable spray, which may be directed, say about the scalp or thru the loose hair of one requiring service. While the effective localizing of the liquid to its supply and nozzle discharge as nebulized, gives the invention embodiment special value for hair dressing use of lacquers, the liquid to be dispersed may be changed to meet other occasions for spraying. Disinfectants, insecticides, and even impregnating or coating substances may be readily applied. Instead of the grip actuated hand pump, continuous pressure supply may be had with a valve control.

What is claimed and it is desired to secure by Letters Patent is:

1. A spray device comprising a central tubular duct, a cup about said duct, said duct having a truncated cylindrical portion provided with a lateral port near the upper end thereof and located approximately at the duct axis, and an aspirator member provided with a passage section having an open bottom for normal submergence in a relatively viscous liquid in said cup and having an open aspirator tip adjacent said lateral port in said duct for pressure flow impingement from said port, said passage section having a continuously increasing cross-section throughout its length from said tip to said open bottom, said aspirator member being attached adjacent said open bottom to said duct and positioned adjacent said truncated portion of said duct, whereby said passage section diminishes capillary flow of the liquid from said cup through said passage section so that the disturbance of the operation of said device due to the viscosity of the liquid is minimized.

2. The device of claim 1 including a pressure supply means, comprising a collapsible bulb surrounding said duct and connected thereto, and an intake check valve located inside said duct.
